UNITED STATES PATENT OFFICE

EMANUEL J. PERRY, OF NEW BEDFORD, MASSACHUSETTS, ASSIGNEE, BY MESNE ASSIGNMENTS TO THE AMERICAN LAUNDRY MACHINERY COMPANY, OF NORWOOD, OHIO, A CORPORATION OF OHIO

FLUID DISCHARGE CONTROL DEVICE

Application filed August 5, 1927. Serial No. 210,848.

In the use of commercial types of laundry machines it is desirable for various reasons to differently dispose of the different washing solutions which may be employed, after each has served its purpose in connection with a given operation. Trenches or other forms of receptacle may be employed to receive the washing solution, a solution of one character being directed into one such trench or 10 receptacle and a solution of another character being directed into another trench or receptacle, thereby keeping the different solutions separate. These conditions make desirable the perfection of some means for 15 selectively directing the washing solution discharged from a machine into one or another of the trenches or other receptacles and it is to such a means that my present invention relates.

It is an object of my invention to provide a fluid deflecting means in connection with the outlet of a washing machine whereby the solution discharged from said machine can be deflected at will into one or another of a 25 plurality of fluid receiving receptacles.

A further object of my invention relates to a novel pedal operated controlling device for said deflecting means.

Other objects relate to details of construction of the deflecting means and to the manner in which such means is adapted to and combined with a washing machine, as well as to the many inherent advantages of such construction and combination.

One embodiment of my invention is illustrated in the accompanying drawings wherein—

Figure 1 is an end elevation of a cylinder type of washing machine having my invention applied thereto;

Figure 2 is a sectional view through the fluid discharge device;

Figure 3 is a front elevation of the complete mechanism;

Figures 4 and 5 are detailed views of the deflector and deflector operating pedal respectively, and

Figures 6 and 7 are end elevations of two modified forms of control mechanism for the deflector device.

In the drawings my invention is illustrated in combination with a washing machine of the cylinder type adapted for commercial use. The reference character 1 designates the outer fluid containing cylinder of such a machine, to which cylinder is applied the structure which embodies my invention. The body of this structure is in the form of a chamber 2 having an opening at its lower end. This chamber is adapted to be placed in communication with the interior of the cylinder 1 by means of any suitable valve controlled conduit fitted into the threaded opening 3 of the chamber. This chamber may be in the form of a casting or may be constructed of sheet metal 55 as desired. The chamber may be secured directly to the bottom of the washing machine cylinder and to this end the upper part thereof may be so designed as to conform to the contour of the cylinder or it may be mounted 60 on the under supports of the machine. A fluid received into the chamber from the washing machine cylinder is adapted to be discharged through the circular opening in the bottom portion of the chamber.

Fitted within the circular opening in the bottom of the chamber is an annular flanged ring 4. The portion which fits within the opening has its inner edges beveled downwardly for the purpose of facilitating the flow of fluid and preventing the lodging of dirt or other foreign matter in the receptacle. The flange formed on the ring is adapted to fit flush up against the bottom edge surface of the chamber and to form therewith a fluid-tight joint. The flange is further provided with a cutaway portion around its periphery constituting an annular seat or shoulder, the purpose of which will be hereinafter described. At diametrically opposite points on the ring there is provided depending journal lugs 6 in which the oscillatable shaft 7 is adapted to be mounted.

A deflector plate of arcuate design is secured to the oscillatable shaft 7 and adapted to be operated thereby. The curvature of this arcuate deflector coincides with that of the annular shoulder 10 in the ring and when these parts are in abutting relation they constitute a substantially fluid-tight joint. The

interfitting relation of the arcuate deflector and the annular shoulder of the ring is quite clearly shown in Fig. 2 of the drawings. It will be seen that when the deflector is in the position in which it is shown in Fig. 1, fluid contained in the chamber will be discharged downwardly and rightwardly whereas when the deflector is moved about its axis to the opposite extreme position the fluid will be discharged downwardly and laterally to the left.

The operating mechanism for the pivoted deflector comprises an arm 11 secured to the shaft 7 and extending generally upward therefrom and carrying at its upper end a laterally projecting pin 12. This pin may if desired be provided with anti-friction roller of any well known type. The opposite end of shaft 7 has secured thereon an upstanding arm 13 which normally lies to one side or the other of a vertical plane passing through the axis of the shaft. The weight 14 is mounted on the opposite end of this arm for the purpose of holding the deflector in the position to which it has been moved. One operating position of the deflector and the weighted arm is shown in Fig. 1 of the drawings. The chamber 2 is provided with a pair of bosses 15 in which the shaft 16 is mounted. This shaft constitutes a support for the oscillatable lever 17 by means of which the deflector is operated. The lever 17 is in the form of a foot pedal having at one end thereof a pedal portion 18.

The operating end of the lever 17 is provided along its upper edge with a pair of opposed inclined cam surfaces 19 and 20 which are separated by a depression or neutral zone 21. These cam surfaces coact with the laterally projecting pin 12 of the arm 11 in order to oscillate the deflector about its axis. The cam surfaces of the lever are so designed and proportioned that a downward movement of the pedal portion 18 causes the inclined surface 19 to move the arm 11 toward the left beyond the vertical plane passing through the axis of shaft 7. The movement in this direction is completed without assistance from the cam lever by virtue of the weight carried by the upper end of the lever 13. This movement carries the deflector to its extreme position opposite to that shown in Fig. 1. If it is desired to return the deflector to its initial position corresponding to that shown in Fig. 1 it is merely necessary to continue the downward movement of the pedal 18 thereby bringing the inclined cam surface 20 into engagement with the pin 12, thus shifting the arm 11 in the opposite direction to a point on the opposite side of the vertical plane above mentioned. The weight again comes into play and completes the movement of the arm and moves the deflector into engagement with the flanged portion of the ring.

From the description set forth in the preceding paragraph it should be apparent that movement of the lever 17 in a single direction is operative to first shift the deflector from one position to another and that a continued movement in the same direction operates to return the deflector to its initial position. The important feature in this construction and arrangement of the parts is that regardless of the position which the deflector may be found to be in, a downward movement of the pedal 18 serves in all cases to shift the deflector to the opposite position. This becomes important where different washing solutions are used successively, inasmuch as it may be desired to discharge the first solution into one receptacle and the second solution into another. This may be exemplified by a washing process involving the use first of a hot washing solution and second of a cold washing solution.

The communication between the receptacle 2 and the washing solution 1 may obviously be effected in numerous different ways without departing from the spirit of the invention. It is contemplated that under certain circumstances it may be desired to provide an opening in the top of the chamber for communication with a registering opening in the bottom of the washing machine cylinder, in which case a gate valve or a valve of any suitable type may be interposed between the bottom of the cylinder for controlling the discharge. It is also contemplated that the chamber 2 may be secured directly to the bottom of the machine cylinder or may be supported by the end frame work of the machine. Variations might also be made with respect to the actuating mechanism for deflector and also with respect to the means for holding the deflector in either of its extreme positions. I have herein shown a bifurcated member 22 which serves as a guide for the oscillating lever 17. This guide as shown is mounted on a rod 23 which may be one of the brace rods of the washing machine frame structure. The specific character of this guide is, however, not important and may be otherwise arranged as desired.

In many instances it is desirable that the control for the deflector device be automatic in its operation and responsive to the temperature of the fluid which is to be discharged. To this end I have provided two alternative forms of control mechanism illustrated in Figures 6 and 7 respectively for positioning the deflecting member in accordance with the temperature of the fluid to be discharged. The mechanism of Figure 6 comprises a thermostat 30 arranged in heat conducting relation with the fluid discharge pipe and having link and lever connections 31, 32 and 33 with the rock shaft 16 on which the deflector actuating cam plate is secured. In Figure 7 I have illustrated a solenoid 42

connected by a lever 43 with the rock shaft 16 for operating the deflector actuating cam plate. This solenoid is controlled by a switch mechanism 41, which switch mechanism is 5 in turn controlled by thermostat 40. By virtue of either of these constructions the deflector member automatically positioned in accordance with whether the fluid be discharged is hot or cold. These control mechanisms automatically fulfill the desired objects of separately discharging hot and cold washing solutions into different receptacles.

What I claim is:

1. In a device of the character described, 15 the combination with a liquid receptacle, of a fluid receiving chamber associated therewith, a valve controlled passage between said receptacle and chamber, said chamber having an open end, an oscillatable shaft diametrically disposed with reference to the open end of said chamber, a deflector secured to said shaft and adapted to coact with the open end of said chamber, manually operable cam means for moving said deflector and automatic means independent of the cam means 25 for detaining the deflector in either of two operative positions.

2. In a device of the character described, 30 the combination with a liquid receptacle, of a chamber secured to said receptacle and having valve controlled fluid communication therewith, said chamber having a circular opening in the lower portion thereof, a flanged ring fitted in said opening, a portion 35 of the periphery of said flanged ring being cut away to form an annular seat or shoulder, diametrically opposed journal lugs depending from said ring, a shaft journaled in said lugs, an arcuate deflector 40 mounted on said shaft, the edges of said deflector being adapted to seat against the said annular shoulder and means for oscillating said deflector.

3. In a device of the character described, 45 the combination with a liquid receptacle, of a chamber secured to said receptacle and having a communication therewith, said chamber having a circular opening in the lower portion thereof, a shaft journaled adjacent 50 said opening, a deflector mounted on said shaft and adapted to coact with said opening to control the direction of flow of fluid discharged therefrom, an arm secured to said shaft and projecting upwardly therefrom at 55 an angle to a vertical plane passing through the axis of the shaft, a weight on said arm, a second arm secured to said shaft and means adapted to coact with said second arm for oscillating said shaft.

4. In a device of the character described, 60 the combination with a liquid receptacle, of a chamber secured to and having communication with said receptacle, an opening in said chamber, a deflector pivoted adjacent said opening and means movable in a single di-

rection for moving said deflector from one position to another and operable upon a continued movement in the same direction to return said deflector to its initial position.

5. In a device of the character described, 70 the combination with a liquid receptacle, of a chamber secured to and having communication with said receptacle, an opening in said chamber, a deflector pivoted adjacent said opening and means movable in a single direction for moving said deflector from one position to another and operable upon a continued movement in the same direction to return said deflector to its initial position, said means comprising an arm secured for movement with said deflector and an oscillatable cam adapted to coact with said arm.

6. In a device of the character described, 75 the combination with a liquid receptacle, of a chamber secured to and having communication with said receptacle, an opening in said chamber, a deflector pivoted adjacent said opening and means movable in a single direction for moving said deflector from one position to another and operable upon a continued movement in the same direction to return said deflector to its initial position, said means comprising an arm secured for movement with said deflector and an oscillatable cam adapted to coact with said arm.

7. In a device of the character described, 85 the combination with a liquid receptacle having a discharge opening, of a deflector pivoted adjacent said opening, and means operable upon movement in one direction to pivot said deflector in either of two opposite directions or successively in both of said opposite directions.

8. In a device of the character described, 90 a fluid discharge chamber having a discharge opening, a flanged ring fitted in said opening, 95 a portion of the periphery of said ring being cut away to form a continuous shoulder, journal bearings on said ring, a shaft journaled in said bearings, a deflector mounted on said shaft, said deflector having divergent edges 100 adapted to separately seat against different parts of said continuous shoulder, and means for oscillating said deflector.

In testimony whereof I affix my signature.

EMANUEL J. PERRY. 120
